SELF-ADJUSTING WRENCH

Francis J. Carnelli, New York, N. Y.

Application September 24, 1948, Serial No. 50,989

3 Claims. (Cl. 81—101)

1

My present invention relates to a wrench, particularly to a self-adjusting pipe wrench capable of gripping pipes of different diameters within a limited range without adjustment.

The invention relates more particularly to a wrench of the type having a jaw fixed at the end of a handle, and a swinging or rocking jaw which closes onto the fixed jaw when swung in one direction and which opens from it when swung in the opposite direction.

Wrenches of this type are designed to engage a pipe or cylindrical surface when the swinging jaw is swung toward the fixed jaw to which it may be urged by a spring.

Objects of my invention are to provide a wrench in which the fixed jaw may be swung in such a manner as to give a maximum range of closures without adjustment, but which may be adjusted to increase this range and also which grips the pipe or cylindrical surface with greater certainty.

Another object of the invention is to provide a wrench in which a pipe or cylindrical surface may be gripped close to the opening edges of the jaws so that a pipe may be engaged and turned even when it is closely adjacent a wall or other obstruction.

The various features of the invention are illustrated, by way of example, in the accompanying drawings in which

Fig. 1 is a side view of a wrench embodying a preferred form of the invention;

Fig. 2 is a view of part of the wrench taken from the right of Fig. 1;

Fig. 3 is a view similar to that of Fig. 1, parts of the wrench being broken away to show features of construction;

Fig. 4 is a sectional view of the wrench taken on line 4—4 of Fig. 1;

Fig. 5 is a sectional view of the wrench taken on line 5—5 of Fig. 1;

Fig. 6 is a perspective view of a spring;

Figs. 7, 8 and 9 are side views of the jaw end of the wrench showing the movable or swinging jaw in different positions of opening;

Fig. 10 is a similar view showing a wrench opened and adjusted to grip a pipe or cylindrical surface near the outer ends of the jaws, as would be the case in turning a pipe closely adjacent a wall or other obstruction.

Referring more particularly to Figs. 1 to 6 inclusive, the wrench comprises a handle 11 having at one end a fixed jaw 12. The jaw 12 may be integral with the handle but, preferably, is a separate block of hardened steel having a wing 13 inserted into a slot in the upper end of the

2

handle and pinned in position by means of a pin 14 (Fig. 5).

The jaw 12 projects forwardly of the front line or side of the wrench which is curved outwardly as at 15 to support the jaw block. The upper or jaw surface of the block 12 is serrated transversely with the serrations pointing slightly forwardly. Immediately below the jaw 12 and projecting from the opposite side of the wrench handle is a box or frame 16 having a transverse opening 17. The upper face of the opening is rounded convexly downwardly as at 18 to form a bearing surface for the collar of a movable jaw 19. Projecting from the side of the wrench into the opening 17 is a rounded fulcrum 20.

The frame 16 is provided with a slot 21 extending longitudinally of the handle 11 and flared forwardly into a groove 22 in the handle intersecting the serrated jaw face of the block 12 and also in an opposite direction.

The swinging jaw 19 is provided with a stem 23 extending through the slot 21 and also with a jaw 24 extending forwardly in confronting relation to the fixed jaw 12. The confronting surface of the jaw 24 is serrated in a direction opposite to the serrations of the jaw 12.

The stem 23 of the swinging jaw 19 has flat sides to fit the sides of the slot 21 and hold the jaw squarely against side sway, and is provided with screw threads 25 in the forward and rear faces to receive an interiorly threaded collar or nut 26.

The collar 26 is encircled by the frame 16, being accessible sidewise of the frame and knurled as at 27 so that it may be rotated by the finger and thumb.

A leaf spring 28 is confined between the lower arm of the frame 16, that is, the arm farthest from the jaw 12, and the lower surface of the collar 26. The lower end of the spring is preferably received in a recess in the frame 16 to hold it against slippage.

The spring, as shown more particularly in Fig. 6, has a pair of arms 29 and 30 spaced to receive the stem 23 and is bent reversely at 31 and 32 into upwardly inclined lengths 33 and 34, bent more sharply upwardly at 35 and 36 to more steeply inclined lengths 37 and 38 and then bent oppositely at 39 and 40 to substantially horizontal lengths 41 and 42 and a connecting part 43.

It will be apparent that the spring is substantially free from contact with the collar 26 except at the length 41, 42 and 43, therefore exerting pressure only at that part of the collar farthest 55 from the handle at the left.

The action of the spring 28 is to rock the fixed jaw counter-clockwise toward closed position. This is a position somewhat more to the right than that shown in Fig. 7. The extreme forward inclination of the face of groove 22 permits the jaw to swing to its extreme forward position with the front end of the movable jaw overhanging the fixed jaw. The spring not only presses the collar 26 upwardly against the convex bearing surface 18 but also presses it forwardly against the rounded fulcrum 20.

When a pipe, such as a small diameter pipe 44, is brought upwardly against the movable jaw surface it rotates the movable jaw clockwise and enters the space between the jaw, the spring 28, however, continues to press the swinging jaw counter-clockwise so that it engages the pipe 44 with a resilient pressure.

When the jaw handle is swung clockwise the serrations of the movable jaw engage the pipe as at 45 as a fulcrum and thereupon the handle swings on the convex bearing surface 18 in a direction to close more tightly on the pipe. The movement is, however, not one purely of pivoting or swinging, for the tendency is for the collar to rock forwardly on the curved bearing surface. This forward rocking is opposed, however, by the rounded fulcrum 20 which limits the forward movement of the collar. Consequently the collar slides on the convex bearing surface and the rounded fulcrum 20 slides slightly upwardly on the side surface of the collar. This changes the direction in which the fixed jaw 12 approaches the movable jaw 24 to cause the serrations to bite into the pipe rather than to slide tangentially. Further swinging of the handle will, of course, turn the pipe. Reverse movement releases the jaws so that they can be moved backward to obtain a fresh grip on a different part of the pipe.

As indicated in Fig. 8 the movable jaw may swing farther apart to grip a larger pipe 45 as, for example, a collar or nipple threaded onto a pipe of smaller dimension. It may swing still further to the open position shown in Fig. 9 to engage a still larger pipe 46, all without adjustment of the collar.

It may be noted as the jaws swing farther apart the collar 26 rocks forwardly on the surface 18 bringing the point of contact closer in line with the pipe and providing a more powerful leverage of the arm on the pipe. It will be understood that by turning the collar 26 the stem 23 may be threaded upwardly to separate the jaws even when the swinging jaw is at its farthestmost or closed position.

As shown in Fig. 10 the collar 26 and stem 23 may be adjusted to grip a pipe such as pipe 47 of any desired diameter at the very foremost edges of the jaws so that a pipe closely adjacent a wall may be securely gripped by swinging the arm of the wrench forward and backward for a short distance and a ratcheting effect is obtained, whereby the pipe may be turned in short successive angles with the relatively small movement of the wrench handle to which it may be limited due to the closeness of adjacent surfaces, such as a wall.

Through the above invention I have, therefore, provided a self-adjusting wrench which permits the maximum self adjustment to different dimensions of pipes and to different positions of the pipe while permitting also the range of these pipe sizes to be adjusted. At the same time the movement, or relative movement, of the jaws is such that when they engage a pipe and pressure

is applied, the serrations of the jaws are forced inwardly into the pipe rather than being swung sidewise. This insures a firm gripping of the pipe and avoids any tendency toward shoving away the surface of the pipe by the serrated edges and consequent slippage of the wrench.

The relationship of the convex bearing surface and the rounded fulcrum together with the spring arranged to give pressure at the rim of the collar farthest from the rounded fulcrum enables the swinging jaw to move smoothly and with certainty to attain the above ends.

The wrench is also of simple construction and may be easily disassembled for repair or replacement of parts. Thus when the collar is threaded past the lower end of the stem 23, the stem may be removed upwardly from the slot of the frame. The collar is held in place by the spring 28 which, for this purpose, is secured in a recess in the lower arm of the frame. However the pressure of the spring does not prevent the collar being swung sidewise out of the frame so that the spring can then be removed.

When the nut 26 is screwed onto the stem or tail 25 so as to bring the jaws 24 and 12 into contact, the jaw 19 may be swung to accommodate a number of pipes of varying small diameters merely by pressing in the end of the stem or tail 25. Also the wrench may be released from gripping position by pressing in the end of the stem or tail 25. By pressing in the end of the stem or tail 25 of the swinging jaw 19 the jaws may be set to grip a pipe in different positions or distances from the open ends of the jaw.

What I claim is:

1. A wrench which comprises a handle having at its upper end a fixed jaw having a serrated jaw face, said handle having a fixed frame projecting rearwardly therefrom and spaced below said jaw face, said frame being slotted vertically and from side to side so as to form transversely spaced windows, the lower surfaces of upper portions of said frame windows having downwardly convex formations, said handle having transversely spaced protuberances extending rearwardly into said frame windows, a movable jaw having a jaw face opposed to the jaw face of said fixed jaw and having a stem extending downwardly through the vertical slot in said frame, a collar mounted within said slot and on said stem, said collar extending into said windows and having an upper surface bearing against and slidably on said convex formations and a spring between said collar and bottom portions of said frame windows to press said collar against said convex bearing surface and against said protuberances.

2. The wrench of claim 1 in which said vertical slot is flared to intersect the serrated jaw surface of said fixed jaw.

3. The wrench of claim 1 in which said bottom portions of said frame windows are recessed downwardly to receive said spring.
